UNITED STATES PATENT OFFICE.

HENRY P. SCHOFIELD, OF CHICAGO, ILLINOIS, ASSIGNOR TO COVEL MANUFACTURING COMPANY, OF CHICAGO, ILLINOIS, A CORPORATION OF ILLINOIS.

SAW-SHARPENING MACHINE.

SPECIFICATION forming part of Letters Patent No. 755,319, dated March 22, 1904.

Application filed May 29, 1903. Serial No. 159,258. (No model.)

To all whom it may concern:

Be it known that I, HENRY P. SCHOFIELD, a citizen of the United States, residing at Chicago, in the county of Cook and State of Illinois, have invented a new and useful Improvement 5 in Saw-Sharpener Machines, of which the following is a specification.

My invention relates particularly to saw-sharpening machines of the type illustrated in reissue patent to Filstrup, No. 11,733, granted April 11, 1899, and my Patent No. 654,844, granted July 31, 1900.

My primary object is to provide improved mechanism for actuating the grinding-wheel gate in a machine of this character.

A further object is to provide improved means for adjusting the feed-finger-carrying arm of such a machine.

The invention is illustrated in the accompanying drawings, in which—

Figure 1 shows a front view of a saw-sharpening machine equipped with my improvements; Fig. 2, an enlarged broken view of the upper portion of the lever or arm which actuates the feed-finger-carrying arm; Fig. 3, a plan section taken as indicated at line 3 of Fig. 2; Fig. 4, a broken side elevational view of the front portion of the machine; Fig. 5, a section taken parallel with the front of the machine as indicated at line 5 of Fig. 4, and Fig. 6 a broken plan section taken as indicated at line 6 of Fig. 4, and showing a detail of the adjustable rack-equipped stop-bar employed.

A description of the preferred construction follows: A represents a frame of the usual general construction; B, the usual saw-guide at the front end of the frame; C, the usual grinding-wheel gate, movable in a guide C' and having journaled in it the arbor of the grinding-wheel C'; C'', a connecting-rod connected with the grinding-wheel gate or slide in the usual manner; D, the usual longitudinally-extending shaft, equipped with cams D' 45 D'' for actuating the grinding-wheel gate and the saw-feeding mechanism, respectively; E, a now well-known rock-lever bearing a novelly adjustable pivoted feed-arm E', equipped

with a feed-finger E''; E'', a connecting-rod joining the lever E to a lever E', actuated by 50 the cam D'; F, a rock-arm having a pivot F', adjustable in a novel manner in a curved slot F'' with which the frame-front is provided below the plane of the shaft D and near the opposite side of the frame; F'', a roller with 55 which the arm F is equipped and which rides upon the cam D'; F'', a projection or extension of the arm F'' beyond its roller, which is provided with a slot F'', with which the lower end of the connecting-rod C'' is adjustably 60 connected to enable it to be aligned with the grinding-wheel gate when the guide of the latter has its inclination changed; F'', a short arm forming an acute angle with the extension F''; F'', an adjustable stop-engaging arm 65 forming an obtuse angle with the arm F; F'', a set-screw serving in the adjustment of the arm F''; F'', an adjustable stop-bar having its inner lateral surface provided with a groove 70 a, its rear edge provided with rack-teeth a', and its upper end equipped with a roller a'', upon which bears the head a'' of the free end of the adjustable arm F''; F'', guide-clips secured to the inner surfaces of the lower and intermediate cross members of the frame-front 75 and having tongues fitting in the groove a of the bar F'', and F'', a bell-crank lever supported on a pivot b at the intermediate member of one side frame of the machine and having a forwardly-turned arm equipped with a 80 toothed segment b', meshing with the teeth a' and having also an upwardly-turned arm terminating in a handle b''.

The frame A is substantially of the usual form, except that it has cast integrally with 85 its front side the curved part provided with the slot F''. The slot F'' is struck on a radius from a point c, which should be the point of contact between the roller F'' and the cam D' and directly above the shaft D, assuming the 90 rock-arm to be in its depressed position. This permits the lower end of the arm F to be swung about the point c in adjustment, so that when the arm F'' is adjusted to change the lower limit of the arc in which the point of 95 connection d between the rod C'' and exten-

sion F^4 oscillates the pivotal point F' may be correspondingly varied, if desired, to prevent decreasing the size of said arc. This aids in adjusting the movements of the grinding-wheel to saws having teeth of the same height but of different inclination, it being understood that the vertical component of the throw of the grinding-wheel gate may be kept a constant by increasing the length of the actuating-arm (at the pivot d) as the inclination of the guides of the gate is decreased toward a horizontal. Moreover, the new adjustment, taken in connection with the old adjustment at d , enables the connecting-rod C^3 to be kept perpendicular to the arm F and parallel with the grinding-wheel gate, which is obviously the best arrangement for the transmission of power. Furthermore, it is obvious that the new adjustment permits the necessary throw to be obtained without unduly lengthening the arm F . Such lengthening of said arm would be objectionable for the reasons, first, that the limits of the frame of the machine prohibit too long an arm; second, that any imperfections at the cam are multiplied at the extremity of the arm; third, that the vibration increases with the length, and, fourth, that the connecting-rod would be thrown seriously out of parallel with the grinding-wheel gate. Finally, the new adjustment enables a rounder cam to be employed than has heretofore been possible, which is an object of a considerable importance. In this connection it may be stated that a rounder cam than the one shown may ordinarily be employed. It is noteworthy that the enumerated advantages may be obtained, in a lesser degree, perhaps, by providing other means for adjustment at the pivot than the particular curved slot and connection shown. It may be added that the relative adjustment of the member F' and the pivot F' may be varied and the location and size of the arc mentioned varied at will, affecting the movements of the grinding-wheel correspondingly. The pivotal connection at F' is, of course, of such a nature as to permit secure connection between the pivot and slot without interfering with the free oscillation of the arm F . The arm F^6 has bolt connection with the base of the arm F^6 at a point f , so that the joint may be of any desired stiffness. The setscrew has screw connection with a lateral projection at the extremity of the arm F^6 , and its point bears upon the arm F^7 . The lever F^{11} works in a slot k , which is provided with a shoulder k' , with which the lever may be thrown into engagement when the grinding-wheel is raised clear from the saw.

Figs. 2 and 3 show in detail the connection between the feed-arm E' and its actuating-arm E . The primary object of this feature is to change the adjustment from the feed-arm itself, as illustrated in Figs. 4 and 5 of my above-mentioned patent, to the upper end of the actuating-arm E . In other words, the

pivot of the feed-arm is to be adjusted on the actuating-arm instead of the feed-arm being adjustable on its pivot, thus permitting adjustment during operation without danger of tilting the feed-arm and disengaging the feed-finger from the saw. Other advantages will be apparent also. In the improved construction the upper end of the lever or actuating-arm E is provided with a hollow rectangular head g , having a guide g' , in which is an adjustable block g^2 . The block g^2 has one side equipped with an integrally-formed plate g^3 , which bears against one face of the head g . The feed-arm is carried by a pivotal bolt g^4 and has a disk g^5 , which forms a plate bearing against the adjacent face of the head g . The bolt g^4 secures the feed-arm to the block g^2 . A longitudinally-immovable screw g^6 , provided with a knob g^7 , serves to adjust the block g^2 with relation to the head g of the actuating-lever.

The guide C' is of adjustable inclination in the usual manner, being pivotally supported at n and equipped with a curved arm n' , having bolt-and-slot connection at its lower end, as indicated in dotted lines in Fig. 1, with a curved stationary support n^2 on the frame. Such a construction is illustrated, for instance, in Fig. 2 of my Patent No. 654,844.

It will be understood that changes in details of construction are contemplated. Hence no undue limitation should be understood from the foregoing detailed description.

What I regard as new, and desire to secure by Letters Patent, is —

1. In a saw-sharpening machine, the combination with the grinding-wheel gate of adjustable inclination and shaft for actuating the same, of a rock-arm connected with said gate, and a pivot for said rock-arm adjustable with relation to said shaft in such manner that said rock-arm may be maintained substantially perpendicular to the connecting-rod of the grinding-wheel gate, for the purpose set forth.

2. In a saw-sharpening machine, the combination with the grinding-wheel gate of adjustable inclination and the shaft for actuating the same, of a rock-arm connected with said gate, a stationary part having a curved slot struck on a radius about a point near said shaft, and a pivot for said rock-arm adjustably secured in said slot, for the purpose set forth.

3. In a saw-sharpening machine, the combination with the grinding-wheel gate of adjustable inclination and the cam of the actuating-shaft therefor, of a rock-arm connected with said gate and having a bearing on said cam, a frame portion having a slot struck on a radius from substantially the point of contact between said cam and arm in the depressed position of said arm, and a pivot adjustably secured in said slot, for the purpose set forth.

4. In a saw-sharpening machine, the combination with the grinding-wheel gate and the cam of the actuating-shaft therefor, of a rock-

arm connected with said gate and having a pivot at one side of said cam, a rack-equipped vertically-movable stop-bar, and an adjusting-lever equipped with a toothed sector meshing with the rack of said bar, for the purpose set forth.

5. In a saw-sharpening machine, the combination with the grinding-wheel gate of adjustable inclination, its connecting-rod, and an actuating-cam, of a rock-arm bearing upon said cam, an adjustable pivot for one end of the rock-arm of a character to permit the rock-arm to be maintained substantially perpendicular to the connecting-rod, and an adjustable stop for the other end thereof, for the purpose set forth.

10. In a saw-sharpening machine, the combination with the grinding-wheel gate, its connecting-rod and an actuating-cam, of a rock-

arm bearing upon said cam, and having an extension adjustably joined to said connecting-rod, a stop-arm pivotally joined to said rock-arm adjacent to said extension, means for adjusting the stop-arm with relation to the rock-arm, and a stop carried by the frame for engaging said stop-arm, for the purpose set forth.

15. In a saw-sharpening machine, the combination with the gate-actuating rock-arm, of a vertically-movable rack-equipped stop-bar, and an adjusting-lever having a toothed sector engaging the rack of said bar, for the purpose set forth.

HENRY P. SCHOFIELD.

In presence of—

W. B. DAVIES,
WALTER N. WINBERG.
